UNITED STATES PATENT OFFICE

PAUL F. W. C. KRIPPENDORF, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY

LAST

Original application filed January 23, 1926, Serial No. 83,376, now Patent No. 1,751,742, dated March 25, 1930. Divided and this application filed August 8, 1929. Serial No. 384,315.

This invention relates to improvements in lasts and is illustrated as embodied in a last adapted for use in the manufacture of shoes of the type disclosed in United States Letters Patent No. 1,751,742, granted March 25, 1930 on my copending application of which this application is a division.

Objects of this invention are to produce a last to be used in the manufacture of shoes which while retaining all the style and shapeliness characteristic of good shoe-making will at the same time so meet the natural requirements of a normal human foot that a shoe constructed thereon will not only be extremely comfortable to wear but will also tend to prevent development of any abnormalities, such for example, as falling arches, and when such deformities have occurred, will tend to correct the same.

From a study of impressions of the normal human foot in plastic material and from considerations of the anatomy of the foot I have discovered that a support for the forepart of the foot, such as the inside of a shoe, should be flat for a considerable area, this area being roughly triangular, the base of the triangle corresponding substantially to the ball line of a last which may be defined as a line extending transversely of the last a short distance (say one-half inch) at the rear of the line joining the anterior ends of the first and fifth metatarsal bones. The apex of the triangle lies between the phalanges of the great toe and the second toe. This flat triangular area should lie in a plane substantially parallel to the tread plane of the shoe, that is, for example, the plane of the tread face of the heel extended forwardly. The forepart area outside of this approximately triangular area should extend upwardly and outwardly to a degree approximating the usual spring of a last.

Accordingly, in an important aspect, the present invention consists in a last having the tread surface of the forepart flat over a substantially triangular area. To this end, the bottom of the forepart of the illustrated last is formed with a substantially flat portion in the form of a triangle the base of

which is substantially at the ball line of the last and the apex of which lies between the great and second toes, the forepart area outside of the triangular area from the ball line forward being directed upwardly and outwardly to an extent substantially approximating the usual spring of a last. In a shoe made on a last of this construction, the surface below the anterior metatarsal arch is flat and hence offers no resistance to the natural flattening of the arch as the foot is bent in walking and at the same time prevents the flattening movement from going too far as would be the case if this surface were transversely concave. Moreover, since the ball line of the shoe at which the bend of the toes should occur in walking is perfectly straight, the maximum flexibility of the sole at this line is afforded, for obviously any transverse curvature of the sole along this line would tend to stiffen the sole.

It is observable that when the foot is pressed lightly on a flat surface the ends of the toes are slightly raised from that surface; hence, by the structure described comprising a flat, triangular area with an upwardly and outwardly extending margin, a support for the toes in their natural position is afforded. This margin which is inclined outwardly and toward the body of the last preferably has a widthwise extent, the projection of which on the plane of the last bottom, as illustrated, is greater than the heightwise displacement of its outer edge above the plane of the last bottom. This construction adds greatly to the comfort of the shoe and tends to prevent friction between the toes and the interior of the shoe during the act of walking.

One of the principal bearing points of the foot is at the head of the fifth metatarsal bone where it joins the cuboid bone. The principal nerves and blood vessels of the foot run along near the outer side of the foot just inside of the bearing point referred to. In fact, most of these nerves and blood vessels will be found to lie approximately above a line drawn from about the center of the breast line to the outer end of the ball line of the shoe. Hence, it is desirable to avoid any pressure upon the bottom of the foot in the

region of this line which would tend to interfere with the nerve control, blood circulation or muscular action.

Accordingly, in accordance with another feature of the present invention, the illustrated last is provided with a shank portion which extends in a straight line from about the center of the breast line of a shoe constructed thereon to a point adjacent the outer end of the ball line. By thus dispensing with any longitudinal arch along this line, pressure such as would interfere, in a shoe constructed upon the usual last, with the free action of the tendons, impede circulation in the blood vessels, or impair the function of the nerves, is avoided.

At each side of the above-mentioned straight line the shank of the illustrated last has a pronounced transverse curvature especially at the inner side of the shank in order that a shoe constructed on the last will fit well into the hollow or longitudinal arch of the inner side of the foot so as to conform to the anatomical structure of the foot.

25 In the drawings,

Fig. 1 is a side elevation of a last used in making the shoe;

Fig. 2 is a perspective view showing the bottom surface of the last illustrated in Fig. 1;

Fig. 3 is a view of the plantar surface of the bones of a normal human foot.

Referring to Figs. 1 and 2, which represent a last 10, it will be seen that there is upon the forepart of the last bottom a flat area bounded by a line having a curved part 12 and a straight part 14. In Fig. 2 a heavy broken line A, B, C, D has been drawn upon the last bottom to assist in describing various characteristics of the last. The line B—C represents substantially the ball line or, as shown in Fig. 3, the line joining the centers of the anterior ends of the first and fifth metatarsal bones. The line C—D is equal in length to B—C, and the angle BCD is a right angle. It is found that the line C—D represents very approximately the direction of the first phalanges, that is, the direction of the great toe. It will be noted that the area enclosed by the triangle BCD approximates the area enclosed by the line 12, 14, the shape of the triangle having been rounded and softened by the curved line 12 and the straight portion 14 corresponding substantially to the ball line of the last. The line 12 defines a shape forward of the ball line approximating the shape of the forepart of the last, and between the line 12 and the periphery 16 of the forepart of the last is a crescent-shaped area 18 which slopes outwardly and upwardly or toward the body of the last from the line 12. This is best seen from Fig. 1 where the last is represented as having the flat surface of its forepart pressed upon a flat tread surface F—G. It will be

seen that the peripheral line 16 extends from the ball line forwardly and upwardly in a gentle curve representing approximately the spring of a usual last. This figure also indicates the vertical curvature of the crescent-shaped surface 18. It will be noted also that the rear portion of the last is raised from the surface F—G a distance representing the height of the heel required for the last. The flat area of the forepart bounded by the line 12, 14 represents the area of the forepart of the foot which presses upon a flat surface in the act of standing. The crescent-shaped marginal area has the described outward and upward inclination for the purpose of supporting the toes in what is their natural position, that is, slightly elevated from the flat tread surface, and the projection of the widthwise extent of the marginal area upon the plane of the last bottom is, as illustrated, substantially greater than the heightwise displacement of the edge of the margin toward the body of the last above the plane of the last bottom.

The line B—C represents approximately the line on which the forepart of the foot bends and the line 14 parallel to it represents the ball line of the last and approximately the line along which the insole of a shoe constructed on applicant's last has to bend in the act of walking. The line along which the insole has to bend is therefore straight and maximum flexibility of the insole is assured since there is no transverse curvature of the sole at the ball line to interfere with its bending. This flat surface along the ball line B—C permits the anterior transverse arch of the foot to flatten out as it naturally does when the toes are bent and pressure is applied to the ground in walking and it prevents this arch from bending too far as is the case when the surface pressed on is concave as it frequently is instead of flat.

The line A—B extends from about the center of the breast line represented by the forward edge of a heel plate 20, secured to the heel-seat of the last, to the outer end B of the ball line and is a straight line, the surface of the shank portion of the last having no vertical curvature along this line.

It has been found that many of the important blood vessels, nerves and tendons of the foot lie adjacent to the vertical plane of the line A—B, and that any upward arch of the shank portion of the shoe along this line tends to produce pressure upon these blood vessels, nerves and tendons and to interfere with circulation, sensation and normal action of the foot muscles. For example, the tendon of a muscle on the inner side of the leg, called flexor longus digitorum, passes downwardly and then horizontally through a groove in the astragalus bone shown at 21 (Fig. 3) and thence in a direction toward the outer end of the ball line. This tendon finally branches

into four parts, one of which is attached to the first phalange of each of the four smaller toes. The tendon is drawn by the muscle through the groove 21 as through a pulley 5 and the portion of the tendon running along the bottom of the foot tends to assume a straight line parallel to the line A—B. It is also especially to be noted that the groove 22 in the plantar surface of the cuboid bone, 10 through which the tendon of the leg muscle peroneus longus passes to its point of attachment at 24 to the posterior portion of the first metatarsal bone, lies over this line. Since the line A—B is a straight line while the foot has a slight natural longitudinal arch above this line, objectionable pressure upon these tendons is avoided. The normal action of the muscle peroneus longus helps in maintaining the posterior transverse arch of the foot and hence my construction, which prevents pressure upon and interference with this tendon and hence with its muscle, avoids a frequent cause of foot trouble.

At each side of the straight line A—B the shank portion of the last is transversely curved as indicated at 6 and 8 in Fig. 2. The portion 8 is curved to conform closely to the longitudinal arch of the foot. The shoe constructed on this last will, therefore, fit closely to the arch of the wearer's foot and will tend to preserve the natural arch of the foot. The transverse curvature of the shank portion affords a support for the shank of the foot in either direction so that the tendency of the wearer to run the shoe over on either side is obviated.

The heel-seat surface of a last represented by the plate 20 is made very convex so that a pronounced cup will be formed in the insole 40 to receive the heel portion of the foot and prevent lateral movement of the foot with respect to the heel, thus avoiding running over of the heel.

Having thus described my invention, what I claim as new and desire to secure by Letters Patent of the United States is:

1. A last having the tread surface of its forepart flat over a substantially triangular area, the base of the triangle being the ball line of the last, and the apex of the triangle lying substantially between the points corresponding to the ends of the first phalanges of the great and second toes.

2. A last having the tread surface of its forepart flat over a substantially triangular area, the base of the triangle being the ball line of the last and the apex of the triangle lying substantially between the points corresponding to the ends of the first phalanges of the great and second toes, the forepart tread surface area outside the said triangular area being directed upwardly and outwardly.

3. A last having a tread surface in which the outer side of the shank portion is substan-

tially straight along a line extending from the center of the heel breast portion to a point adjacent to the outer end of the ball line.

4. A last having a tread surface in which the outer side of the shank portion is substantially straight along a line extending from the center of the heel breast portion to a point adjacent to the outer end of the ball line, the shank portion of the last curving sharply upwardly on both sides of the line.

5. A last for welt shoes having the margin of its forepart only inclined outwardly and toward the body of the last, the projection of the widthwise extent of said inclined margin upon the plane of the last bottom being substantially greater than the heightwise displacement of its outer edge above the plane of the last bottom, and the widthwise extent and the heightwise displacement of the margin increasing toward the toe end of the last whereby the heightwise displacement of the outer edge of the inclined margin approximates the spring of an ordinary last.

In testimony whereof I have signed my name to this specification.

PAUL F. W. C. KRIPPENDORF.
